BOX EJECTOR

Gerald C. Paxton, Santa Ana, Calif., assignor, by
mesne assignments, to Food Machinery Cor-
poration, a corporation of Delaware

Application September 24, 1935, Serial No. 41,895

13 Claims.

(Cl. 1—10)

My invention relates to machines for securing covers on containers and more particularly to a suitable mechanism for discharging or ejecting a container from such a machine after the cover securing operation.

In the agricultural industry, fruits, vegetables and other produce are packed in suitable crates or boxes for transportation to market. After being packed, these containers are conveyed to a lid securing machine where a lid is secured on the container. After the lid has been so secured, the container is usually discharged from the lid securing machine onto a suitable storage conveyor where the containers are collected awaiting shipment. As these storage conveyors are usually of the idle roller type, it is necessary that the lidded container be ejected from the machine with sufficient force to carry the container to its destination. It is also necessary, in view of the high rate of speed at which these machines must operate, that the lidded containers be promptly ejected from the machine so that the next following container may be immediately received by the machine.

It is, accordingly, an object of my invention to provide a box ejector for use on a lid securing machine that will eject a box with sufficient force to propel the box a substantial distance along an idle conveyor leading therefrom.

Another object of my invention is to provide a box ejector (for use on a lid securing machine) that is prompt in action so as to completely eject a box by the time the machine completes a lidding operation cycle.

Lid securing machines at present are generally of two types. One known as a lidding machine presses the lid on the box for nailing thereto. The other is known as a strapping machine and further secures the lid in place by applying a strap across the middle of the lid and securing ends of the strap to sides of the box. The invention is disclosed herein as associated with a lidding machine.

Other objects and advantages will be made manifest in the following description, taken in connection with the accompanying drawings, in which:

Fig. 1 is a front elevational view of a lidding machine which includes a preferred form of box ejector of my invention, certain portions of the lidding machine, not pertaining to the present invention, being broken away.

Fig. 2 is a horizontal sectional view taken on the line 2—2 of Fig. 1.

Fig. 3 is a fragmentary side elevational view

looking in the direction of the arrow 3 of Fig. 1.

Fig. 4 is a vertical sectional view taken on the line 4—4 of Fig. 2, and showing the operation of the ejector of my invention at the time a box is being received by the lidding machine.

Fig. 5 is a view similar to Fig. 4, but showing the operation of my invention during the lidding of a box by the lidding machine.

Fig. 6 is a fragmentary side elevational view looking in the direction of the arrow 6 of Fig. 5.

Fig. 7 is a view similar to Fig. 6, but showing the operation of my invention during the time a box is being ejected from the lidding machine, and

Fig. 8 is an enlarged, fragmentary sectional view taken on the line 8—8 of Fig. 2.

Referring specifically to the drawings, a lidding machine 10, shown in connection with a preferred embodiment of my invention, is illustrated in Fig. 1, this machine including a frame 11, a power unit 12, a box supporting table 13, a box ejector 14, nailing units 15 and a strap applying unit 16. With the exception of the box ejector 14, the machine 10 is substantially similar to the machine disclosed in the copending application of Hale Paxton et al., Serial No. 688,104, filed September 5, 1933, for Automatic lid nailing and strapping machine.

The frame 11 includes front and rear corner posts 16 and 17 respectively extending upward from a suitable base 18 shown in Fig. 2. Secured to the posts 16 and 17 at either side of the machine 10 are horizontal bars 19, the latter supporting opposite ends of a horizontal channel member 20 as shown in Fig. 5. Mounted on the upper ends of the posts 16 and 17 is a suitable superstructure 22 for supporting the nailing units 15 and strapper 16.

The power unit 12 is mounted between the base 18 and the channel member 20, this unit serving to raise and lower the table 13, the construction and operation of the unit 12 being clearly set forth in the above referred to application.

The table 13, shown in Fig. 2, includes transverse bars 25 and 26, with their ends disposed in sliding relation with the corner posts 16 and 17. Extending between the bars 25 and 26 are pairs of longitudinal bars 27 having rollers 28 mounted therebetween. Provided on the front and rear sides of the table 13 are side flushers 29 mounted on shafts 30, the ends of the latter being rotatably received by the bars 25 and 26 as shown in Fig. 2. Fixed to and extending upward from the shafts 30 are arms 31 having flusher plates 32 on the upper ends thereof. Mounted on the arms 31

are horizontal bars 34 having stiff springy ends 34a for centralizing a box transversely on the table 13 and fixed to the outermost arms 31 above the bars 34 are box end engaging members 35 for centralizing a box longitudinally on the table 13 in a manner to be described hereinafter. Fixed on opposite ends of each of the shafts 30 is a lever 38 having a roller 39 on the upper end thereof, each of the rollers 39 being disposed in alignment 10 with a cam track 40 provided on the nearest one of the posts 16 and 17 as shown in Figs. 5 and 6, the tracks 40 having angular portions 41 at the lower ends thereof. The arms 38 are urged to the positions in which they are shown in Fig. 3 by contractile springs 42.

The box ejector 14 includes a horizontal shaft 50 secured at its ends to the transverse bars 25 and 26 of the table 13. Fixed on the shaft 50 adjacent the bar 26 is a stationary block 51 bifurcated at its lower side to receive and rotatably support a pulley 52. Pivotaly mounted on a pin 54 on the upper side of the block 51 is box stop 55 urged to the position in which it is shown in Fig. 8 by a compression spring 56. Slidably 20 mounted on the shaft 50 is a block 58 having a pin 59 on the upper side thereof. Pivotaly mounted on the pin 59 is a box end engaging hook 60 urged to the position in which it is shown in Fig. 8 by a compression spring 61. Extending 25 from the block 58 over the pulley 52 is a chain 63, the lower end of which hangs through a suitable opening provided in the channel member 20 as shown in Fig. 4. Attached to the extremity of the chain 63 is a rod 64 having a head 65 on its lower end and a sliding collar 66 on its upper end, there being a compression spring 67 on the rod 64. Fixed on the shaft 50, as seen in Fig. 4, are collars 68 and 69, an extension spring 70 being mounted on the shaft 50 and secured at its ends to the fixed collar 68 and sliding block 58.

40 Rotatably mounted on the shaft 50 (Fig. 3) adjacent the collar 69 (Fig. 2) is a box stop 72 having an apertured ear 73 extending from one side thereof. The stop 72 is normally urged 45 against the collar 69 by a compression spring 75 coiled about the shaft 50.

Mounted on a suitable bracket 78 provided on the under side of the table 13 is a bell crank 79 having arms 80 and 81. Connecting the arm 80 50 of the bell crank 79 with the ear 73 of the box stop 72 is a link 82 and connecting the arm 81 of the bell crank with one of the levers 38 of the front shaft 30 is a compressible link 83, the latter being normally urged to extended position by a 55 compression spring 84 as shown in Fig. 3.

Operation

When a packed box B is delivered from a conveyor 90 to the table 13, as shown in Fig. 4, the 60 stop 55 and hook 60 are depressed allowing the box to strike the stop 72. When the box strikes the stop 72, the latter is moved leftward against the pressure of the spring 75 as shown by the dotted line position indicated at a in Fig. 4, thus 65 allowing the box B to pass over the stop 55 permitting the latter to rise behind the box to the position indicated in dotted lines. After the box B is stopped, the spring 75 returns the stop 72 to the dotted line position indicated at b, thus 70 urging the box against the stop 55.

When the box is positioned on the table 13 between the stops 55 and 72, the operator causes the power unit 12 to be energized thus raising the table 13 toward the nailing units 15. As the 75 table 13 rises, the side flushers 29 are swung in-

ward by contact of the tracks 40 with the rollers 39 of the levers 38 so that the members 35 engage opposite ends of the box B. As the side flushers 29 are swung inward, the link 83 rocks the bell crank 79 causing the link 82 to rotate the stop 5 72 out of engagement with the box end as shown in Fig. 6. As the stop 72 is rotated, it is also urged against the collar 69 and partially under the end of box B as shown in Fig. 5. During the upward travel of the table 13, the chain 63 is held 10 at its lower end by the member 20 thus pulling the block 58 toward the block 51 until the hook 60 engages the end of the box B, the spring 70 being now extended as shown in Fig. 5.

When the table 13 approaches its uppermost 15 position, the lid L, shown in Fig. 1, is pressed over the contents of the box and the lid ends are nailed to the box ends by the nailing units 15 substantially as set forth in the above referred to co-pending application. 20

As the table 13 is lowered following the lid securing operation, the chain 63 becomes slack allowing the hook 60 to be urged against the box end by the spring 70, the box being retained on the table 13 by the members 35 of the side flushers 29. When the rollers 39 roll down the portions 41 of the tracks 40, the flushers 29 swing outward as shown in Fig. 7, allowing the stop 72 to rise against the under side of the box B, the link 83 being telescoped longitudinally against 30 the pressure of the spring 84 thereof. As soon as the members 35 of the flushers 29 move out from engagement with the ends of the box, the latter is quickly ejected from the table 13 onto a suitable idle roll discharge conveyor 91 by the 35 spring 70 and hook 60. Ejection of the box B is started before the table 13 arrives at its lowermost position, the box being completely discharged from the machine 10 at substantially the same time that the table 13 comes to rest. When 40 the ejected box passes over the stop 72, the link 83 is extended by the spring 84 causing the stop 72 to be swung upward into position to stop the next box to be received by the table 13.

Although I have shown and described but one 45 preferred embodiment of my invention, it is to be understood that many modifications and changes might be made therein without departing from the spirit of the invention or the scope of the appended claims. 50

What I claim is:

1. In a lid securing machine, the combination of: a horizontal table for supporting a loaded box; idle conveyor rollers provided on said table to support and facilitate rapid movement of said box over said table; means adapted to cooperate with said table when in superimposed contact with a box on said table to perform a lid securing operation on said box; mechanism causing relative vertical movement between said table and said means to effect said contact; box ejecting means mounted on said table beneath the path of a box travelling over said table; and means controlled by said mechanism and connected to said ejecting means to move the latter to engage a 65 rear face of said box, said ejecting means quickly expelling said box from said machine after the performance of said lid securing operation.

2. In a lid securing machine, the combination of: a horizontal table for supporting a loaded box; idle conveyor rollers provided on said table to support and facilitate rapid movement of said box over said table, there being an open longitudinal space provided in said table between said rollers; means adapted to cooper- 75

ate with said table when in superimposed contact with a box on said table to perform a lid securing operation on said box; mechanism causing relative vertical movement between said table and said means to effect said contact; a shaft mounted longitudinally on said table in said space; a box ejector slidably mounted on said shaft and adapted to extend up into the path of a box travelling over said table or downwardly out of said path; means controlled by said mechanism and connected to said ejector to position said ejector opposite a rear face of said box and means for causing said ejector to slide rapidly along said shaft to quickly expel said box from said table after the performance of said lid securing operation.

3. In a lid securing machine, the combination of: a horizontal table for supporting a loaded box; idle conveyor rollers provided on said table to support and facilitate rapid movement of said box over said table, there being an open longitudinal space provided in said table between said rollers; means adapted to cooperate with said table when in superimposed contact with a box on said table to perform a lid securing operation on said box; mechanism causing relative vertical movement between said table and said means to effect said contact; a shaft mounted longitudinally on said table in said space; a box ejector slidably mounted on said shaft and adapted to extend up into the path of a box travelling over said table or downwardly out of said path; means controlled by said mechanism and connected to said ejector to position said ejector opposite a rear face of said box; means for causing said ejector to slide rapidly along said shaft to quickly expel said box from said table after the performance of said lid securing operation; a box stop mounted on said shaft; and means controlled by said mechanism to deflect said stop out of the path of a box on said table to permit said box to be expelled by said ejector.

4. In a lid securing machine, the combination of: a horizontal table for supporting a loaded box; idle conveyor rollers provided on said table to support and facilitate rapid movement of said box over said table; means adapted to cooperate with said table when in superimposed contact with a box on said table to perform a lid securing operation on said box; mechanism causing relative vertical movement between said table and said means to effect said contact; a shaft horizontally mounted on said machine adjacent the path travelled by a box moving over said table and parallel with the direction of said travel; stop means mounted on said shaft for stopping a box in position to be operated on; a box ejector slidably mounted on said shaft and adapted to be shifted into and out of said path; means controlled by said mechanism and connected to said ejector to move said ejector to engage a rear face of said box; and means for shifting said ejector to quickly expel said box from said machine after the performance of said lid securing operation.

5. In a lid securing machine, the combination of: a horizontal table for supporting a loaded box; idle conveyor rollers provided on said table to support and facilitate rapid movement of said box over said table; means adapted to cooperate with said table when in superimposed contact with a box on said table to perform a lid securing operation on said box; mechanism causing relative vertical movement between said table and

and said means to effect said contact; a shaft horizontally mounted on said machine adjacent the path travelled by a box moving over said table and parallel with the direction of said travel; a box stop rotatably and slidably mounted on said shaft and adapted to extend into the adjacent path; means for yieldably urging said stop to slide in a given direction on said shaft; means for limiting the sliding movement of said stop on said shaft responsive to said yieldable means; and means for rotating said stop about said shaft to remove said stop from the adjacent path of said box.

6. In a lid securing machine, the combination of: a horizontal table for supporting a loaded box; idle conveyor rollers provided on said table to support and facilitate rapid movement of said box over said table; means adapted to cooperate with said table when in superimposed contact with a box on said table to perform a lid securing operation on said box; mechanism causing relative vertical movement between said table and said means to effect said contact; a shaft horizontally mounted on said machine adjacent the path travelled by a box moving over said table and parallel with the direction of said travel; a box stop rotatably and slidably mounted on said shaft and adapted to extend into the adjacent path; means for yieldably urging said stop to slide in a given direction on said shaft; means for limiting the sliding movement of said stop on said shaft responsive to said yieldable means; and means controlled by said mechanism to automatically rotate said stop about said shaft to remove said stop from the adjacent path of said box.

7. In a lid securing machine, the combination of: a horizontal table for supporting a loaded box; idle conveyor rollers provided on said table to support and facilitate rapid movement of said box over said table; means adapted to cooperate with said table when in superimposed contact with a box on said table to perform a lid securing operation on said box; mechanism causing relative vertical movement between said table and said means to effect said contact; a shaft horizontally mounted on said machine adjacent the path travelled by a box moving over said table and parallel with the direction of said travel; stop means mounted on said shaft for stopping a box in position to be operated on; a box ejector slidably mounted on said shaft and adapted to be shifted into and out of said path; yieldable energy storage means connected to said ejector and receiving energy from said mechanism during said relative vertical movement to cause said ejector to engage a rear face of and quickly expel said box from said machine after the performance of said lid securing operation.

8. In a lid securing machine, the combination of: a horizontal table for supporting a loaded box; idle conveyor rollers provided on said table to support and facilitate rapid movement of said box over said table; means adapted to cooperate with said table when in superimposed contact with a box on said table to perform a lid securing operation on said box; mechanism causing relative vertical movement between said table and said means to effect said contact; a shaft horizontally mounted on said machine adjacent the path travelled by a box moving over said table and parallel with the direction of said travel; a box ejector slidably mounted on said shaft and adapted to be shifted into and out of said path; a spring

coiled about said shaft and connected to said ejector; and means actuated by said mechanism during said relative vertical movement to distort said spring, the energy of said distortion being imparted to said ejector through said spring to move said ejector against the rear face of said box; and means to hold said box against movement and then release said box to permit said ejector to quickly expel the box from said machine.

9. In a lid securing machine, the combination of: a horizontal table for supporting a loaded box; idle conveyor rollers provided on said table to support and facilitate rapid movement of said box over said table; means adapted to cooperate with said table when in superimposed contact with a box on said table to perform a lid securing operation on said box; mechanism causing relative vertical movement between said table and said means to effect said contact and to then restore the normal spaced relation between said table and said means; a shaft horizontally mounted on said machine adjacent the path travelled by a box moving over said table and parallel with the direction of said travel; a box ejector slidably mounted on said shaft and adapted to be shifted into and out of said path; a spring coiled about said shaft and connected to said ejector; and means actuated by said mechanism during said relative vertical movement to stretch said spring and slidably retract said ejector along said shaft into a position with said ejector disposed adjacent a rear face of said box, said last recited means in the restoration of said normal spaced relation permitting said spring to urge said ejector against said rear face of said box; and means to resist the movement of said box on said table by said ejector and then release said box as the completion of the aforesaid relative vertical movement is approached to permit said ejector to quickly expel said box from said machine.

10. In a lid securing machine, the combination of: a horizontal table for supporting a loaded box; idle conveyor rollers provided on said table to support and facilitate rapid movement of said box over said table; means adapted to cooperate with said table when in superimposed contact with a box on said table to perform a lid securing operation on said box; mechanism causing relative vertical movement between said table and said means to effect said contact and for causing a second relative vertical movement between said table and said means to restore the normal spaced relation between said means and said table; a shaft horizontally mounted on said machine adjacent the path travelled by a box moving over said table and parallel with the direction of said travel; a box ejector slidably mounted on said shaft and adapted to be shifted into and out of said path; a spring coiled about said shaft and connected to said ejector; and means actuated by said mechanism during the first aforesaid

relative vertical movement to stretch said spring and slidably retract said ejector along said shaft into a position with said ejector disposed adjacent a rear face of said box, said last recited means during the second aforesaid relative movement permitting said spring to urge said ejector against the rear face of said box and quickly expel said box from said machine.

11. In a lid securing machine, the combination of: a horizontal table for supporting a loaded box; idle conveyor rollers provided on said table to support and facilitate rapid movement of said box over said table; means adapted to cooperate with said table when in superimposed contact with a box on said table to perform a lid securing operation on said box; means for elevating said table to effect said contact; a box ejector mounted adjacent the path travelled by said box in moving over said table, said ejector being shiftable into and from said path; spring means adapted to yieldably urge said ejector in the direction of said travel; and means actuated by said elevating means during the lifting of said table to store energy in said spring means, said last recited means permitting the release of said energy with said ejector engaging a rear face of said box to quickly expel said box from said machine during the downward movement of said table.

12. In a lid securing machine, the combination of: a frame; a horizontal table for supporting a loaded box; idle conveyor rollers provided on said table to support and facilitate rapid movement of said box over said table; means adapted to cooperate with said table when in superimposed contact with a box on said table to perform a lid securing operation on said box; means for elevating said table to effect said contact and for lowering said table; a box ejector mounted on said table adjacent the path travelled by said box in moving over said table, said ejector being shiftable into and from said path; spring means mounted on said table adapted to yieldably urge said ejector in the direction of said travel; a pulley on said table; and a linear flexible element connected to said ejector passing over said pulley and connected to the frame of said machine, said flexible element operating during the upward movement of said table to shift said ejector into a position opposite a rear face of said box and releasing said ejector during the downward travel of said table to permit said spring to urge said ejector against said box to quickly expel said box from said machine.

13. A combination as in claim 1, in which means is provided for shifting inwardly at opposite sides of said box to engage said box and substantially delay longitudinal movement of said box in response to said ejector, said means releasing said box in timed relation with a reversal of said relative vertical movement.

GERALD C. PAXTON.
